UNITED STATES PATENT OFFICE.

FRANK L. DYER, OF MONTCLAIR, NEW JERSEY.

ASSEMBLY-VOTING MACHINE.

1,308,279.

Specification of Letters Patent.

Patented July 1, 1919.

Original application filed February 2, 1915, Serial No. 5,601. Divided and this application filed March 23, 1917. Serial No. 156,822.

To all whom it may concern:

Be it known that I, FRANK L. DYER, a citizen of the United States, and a resident of Montclair, county of Essex, and State of New Jersey, have invented a certain new and useful Improvement in Assembly-Voting Machines, of which the following is a specification.

The present application is a division of my application for Letters Patent filed February 2, 1915, Serial No. 5601, for assembly voting machines.

My invention relates to improvements in assembly voting machines of the type disclosed and claimed by me in Patent No. 701,314, dated June 3, 1902, and by means of which I enlarge the scope and improve the operation of the apparatus.

With the apparatus disclosed in my patent, I make use of a transmitter located at each member's desk, or adjacent to his seat, by means of which one or the other of two circuits could be closed, corresponding to the two votes "Yes" or "No."

In my application for Letters Patent filed February 2, 1915, Serial No. 5601, I disclosed certain improvements on the apparatus shown in said patent, by which, instead of printing only two kinds of votes, affirmative and negative, I provide also for making a record of such members who may wish to vote "Present," as well as of those who may wish to vote "Paired," and of those who do not vote at all. In this way a very complete printed record will be secured. My present improvements relate particularly to the sending device for transmitting the vote of the individual member to a suitable recording machine, preferably of the general type disclosed in my said patent.

In order that the invention may be better understood, attention is directed to the accompanying drawings, forming a part of this specification, and in which—

Figure 1 is a front view of one of the transmitting devices, showing the front broken way to disclose the indicator disk;

Fig. 2 is a longitudinal sectional view of Fig. 1;

Fig. 3 is a section on the line 3—3 of Fig. 2;

Fig. 4 is a section on the line 4—4 of Fig. 2;

Fig. 5 is a section on the line 5—5 of Fig.

2; the view being taken in the direction of the arrow looking toward the front of the transmitter;

Fig. 6 is a detail perspective view showing the contact disk in the transmitter; and

Fig. 7 is a front view of one of the polarized magnets preferably used in the transmitter.

In the above views corresponding parts are represented by the same reference numerals.

Referring to these drawings, 15 represents a casing containing the transmitting mechanism. Mounted therein is a lock barrel 16, preferably a Yale lock, carrying a pointer 17, adapted to move with respect to the indications "Not voting," "Yes," "No," "Present," and "Paired" appearing on the face of the casing, so as to guide the member in determining how far to turn the lock barrel to vote as he desires. The lock barrel carries a gear 18 on its inner end, which meshes with a gear 19 loosely mounted on the shaft 20. The gear 19 carries a pin 21, which engages with an arm 22 (see Fig. 5) so that when the lock barrel is turned in one direction, the pin engaging the arm 22 will move the shaft 20 for a part of a revolution, but when the lock barrel is moved in the opposite direction to withdraw the key, the pin 21 will move away from the arm 22, so as to leave the shaft 20 in its locked position. The shaft 20 carries a toothed wheel 23, having five teeth (see Fig. 4), corresponding to the five positions, and with which the tooth 24, on the armature 25 of a polarized magnet 26, engages. The polarized magnet 26 is provided with a yoke 27 having forwardly extending pole pieces 28, between which the armature 25 is mounted, as shown in Fig. 7, so that the armature will be polarized and hence will respond to currents of one polarity, but not to currents of the opposite polarity. Coöoperating with the armature 25 is a latch 29, having a finger 30, so arranged that when the armature 25 is attracted to withdraw the tooth 24 from one of the teeth of the toothed wheel 23, the armature will be locked behind the finger 30 so as to hold the tooth 24 away from the toothed wheel, and therefore permit the toothed wheel to move to the return position. A pin 31 on the toothed wheel 23 engages the tail 32 of the latch 29, so as to force the latch downwardly

100
105
110

just as the toothed wheel approaches its backward position, to thus withdraw the finger 30 from the end of the armature 25 and permit the armature to again be moved 5 with the tooth 24 in engagement with the first tooth of the toothed wheel 23, corresponding to the "not voting" position.

The gear 19 engages a pinion 33, mounted on a shaft 34 and adapted to drive an escape 10 wheel 35 through a ratchet and pawl 36, as shown in Fig. 5. The parts are so arranged that when the lock barrel is turned to move the shaft 20 into the desired voting position, the gear 19, rotating the pinion 33, 15 will move the pawl with respect to the ratchet so as not to turn the escape wheel 35. When, however, the shaft 20 is released, as will be explained, the pawl will engage the ratchet and the escape wheel will be 20 turned, operating the escapement 37 and causing the return movement of the shaft 20 to be retarded, thus permitting a gradual return of the parts to their original position. A spring 38 on the shaft 20 is wound 25 up when the shaft is advanced, and its tension returns the shaft to its normal position when the shaft is released. The tail of the escapement 37 works in close proximity to a brake magnet 39, so that when the magnet 30 is energized it will lock the escapement and prevent the parts from moving. When, however, the magnet is not energized, the escapement can vibrate freely to allow the 35 parts to slowly return to their original position. The magnets 26 and 39, at each transmitting station, are arranged in series.

On the shaft 20 is an insulating disk 40, carrying a single contact 41, which is connected to a collecting ring (see Fig. 6) with 40 which a brush 42 engages to close the circuit to the contact 41. Engaging the periphery of the disk 40 are five contacts 43, each carried on springs, as shown, and with which the contact piece 41 is adapted to successively make contact. These contacts 43 correspond to the special circuits leading to the recording apparatus and controlling the five varieties of votes, and the common return circuit of said contacts includes the magnets 45 26 and 39, as described in said application. At the front of the shaft 20 is a disk 44, carrying the representations "Not voting," "Yes," "No," "Present," and "Paired," one of which indications will be observed 50 through an opening 45 in front of the casing, covered by a glass window 46, thus confirming the vote that the member desires to transmit.

In order to reset the apparatus so as to permit a correction in the vote, I show a small lever 47 on the front of the casing mounted 60 on a shaft 48. This lever is provided with a cam 49, which engages the tail 50 of the armature 25, so that when the lever 47 is

operated it will withdraw the tooth 24 from the toothed wheel 23 and thereby release the toothed wheel so as to permit the shaft 20 to return to its original position. The shaft 48 is also provided with a cam 51, engaging a circuit spring 52, so as thereby to 70 short-circuit and thus disable the brake magnet 39.

In operation, when a member desires to vote, he inserts his key in the lock 16 and turns it to the required position. If he 75 votes "Yes," the second tooth of the disk 23 will lock the shaft 20 in that position with the word "Yes" disclosed in the opening 45. If he votes "No" the toothed disk would be locked in the next position, and so on, this 80 locking being effected by the tooth 24 on the armature 25 engaging the tooth of the disk and preventing the return movement of the disk. The contact device 41 will be brought beneath and locked in contact with one or 85 the other of the contacts 43, to thereby close the circuit to the desired selecting magnet of the recording device. If the member desires to change his vote, he actuates the small lever 47 and the cam 49 withdraws the tooth 90 24 of the armature 25 away from the toothed disk 23, so as to release the shaft 20, and the spring 38 returns the shaft to its normal 95 position, a stop (not shown) limiting this movement.

In order to prevent the brake magnet 39 from locking the shaft 20 during the resetting operation at a midway position when the contact 41 passes into engagement with one of the contact springs 43, I use the cam 100 51, actuating the contacts 52, so as to short-circuit the brake magnet during this return movement. After all the members have voted, the recording apparatus, preferably 105 of the type disclosed in my said patent, is operated. When the collecting device thereof engages the contact plate or plates corresponding with any particular transmitter, it 110 closes the circuit to the desired selecting magnet, which determines the particular list in which the member's name is to be printed. The closing of this circuit energizes the magnet 26 and withdraws the tooth 24 from the toothed wheel 23, and the magnet 26 will be locked in its withdrawn position by the finger 30 of the latch 29. The shaft, however, 115 will not immediately return because the brake magnet 39, being in series with the magnet 26, will be energized, and the escapement 37 will hold the shaft 20 from rotating. When, however, the circuit is broken at the receiving or recording device, the magnet 39 will be deenergized, allowing the escapement 37 to vibrate and thus freeing the shaft 20, and the spring 38 will return 120 the shaft slowly to its original position. Near the end of this movement, the pin 31 engages the tail 32 of the latch 29, so as to 125

free the armature 25, which will again be moved in contact with the toothed wheel 23, ready for the next operation. The return of the shaft 20 to its original position will 5 bring the words "Not voting" opposite the opening 45, so that the member will know that his vote has been received. It will be observed that if a member does not vote, so that the apparatus will not be actuated, the

10 tooth 24 will remain in engagement with the first tooth of the wheel 23 and the contact 41 will remain in engagement with the lower contact 43 in circuit with the particular selecting magnet corresponding with the 15 "Not voting" list, so that the member's name will be printed in the list of "Not voting."

Having now described my invention, what I claim as new and desire to secure by Letters Patent, is as follows:

20 1. In a transmitter for assembly voting apparatus of the type described, the combination with a shaft, a contact device carried thereby, means for locking the shaft in any one of its successive positions, a spring for 5 returning the shaft to its normal position when released, and means for retarding the return movement of the shaft, substantially set forth.

2. In a transmitter for assembly voting 30 apparatus of the type described, the combination with a contact device adapted to make contact with any one of successive circuits, means for locking the contact device in its set position, a magnet for releasing 35 the contact device, and a brake magnet for locking the contact device against return movement during the recording operation, substantially set forth.

3. In a transmitter for assembly voting 40 apparatus of the type described, in combination with a contact device adapted to make contact with any one of successive circuits, means for locking the contact device in its set position, a magnet for releasing 45 the contact device, and a brake magnet for locking the contact device against return movement during the recording operation, said magnet being connected in series in a common return for all of said circuits, substantially set forth.

50 Copies of this patent may be obtained for five cents each, by addressing the "Commissioner of Patents, Washington, D. C."

4. In a transmitter for assembly voting apparatus of the type described, the combination with a contact device adapted to make contact with any one of successive circuits, means for locking the contact device 55 in its set position, an escapement for retarding the return movement of the contact device, and a brake magnet coöperating with said escapement to lock the same during the recording operation, substantially set forth. 60

5. In a transmitter for assembly voting apparatus of the type described, the combination with a contact device adapted to make contact with any one of successive circuits, means for locking the contact device 65 in its set position, an escapement for retarding the return movement of the contact device, a brake magnet coöperating with said escapement to lock the same during the recording operation, and means for manually 70 releasing the contact device and simultaneously disabling the brake magnet, substantially set forth.

6. In a transmitter for assembly voting apparatus of the type described, the combination with a contact device adapted to make contact with any one of successive circuits, an armature for locking the contact device in its set position, a magnet for actuating the armature, and a latch for locking 75 the armature in its withdrawn position, substantially set forth.

7. In a transmitter for assembly voting apparatus of the type described, the combination with a contact device adapted to 80 make contact with any one of successive circuits, an armature for locking the contact device in its set position, a magnet for actuating the armature, a latch for locking 85 the armature in its withdrawn position, and means for tripping said latch near the end 90 of the return movement of the contact device, substantially set forth.

This specification signed and witnessed this twenty-second day of March, 1917.

FRANK L. DYER.
